UNITED STATES PATENT OFFICE.

NORRIS E. GOODRICH, OF BATTLE CREEK, MICHIGAN, ASSIGNOR, BY MESNE ASSIGNMENTS, TO SANITARIUM EQUIPMENT COMPANY, OF BATTLE CREEK, MICHIGAN, A CORPORATION OF MICHIGAN.

LIGHT-TREATMENT APPARATUS.

Application filed October 30, 1926. Serial No. 145,229.

The main objects of this invention are:

First, to provide an improved light treatment apparatus which is highly desirable for the purpose and very economical to use.

5 Second, to provide a light treatment apparatus which employs arc lamps, the same being arranged so that the operator and patient are effectively protected.

10 Objects pertaining to details and economies of my invention will definitely appear from the detailed description to follow. The invention is clearly defined and pointed out in the claims.

15 A structure embodying the features of my invention is clearly illustrated in the accompanying drawing forming a part of this application, in which:

20 Fig. 1 is a perspective view of an apparatus embodying the features of my invention with the table partially withdrawn from the cabinet.

25 Fig. 2 is a front elevation with parts sectioned for convenience in illustration.

Fig. 3 is a diagrammatic view illustrating 25 the wiring for the lamps and the lamp controlling rheostat.

30 Referring to the drawing, I provide a cabinet frame consisting of corner uprights 1 connected by top and bottom longitudinal members 2 and 3, respectively, and top and bottom end members 4 and 5.

35 These members are connected to provide a rigid frame, the details not being illustrated.

On the inner sides of the uprights are track supporting brackets 6 carrying the tracks 7. The table 8 is supported at its inner end by the rollers 9 traveling on these tracks, the rollers being mounted on an axle 10 which is supported between axle brackets 11 on the under side of the table.

40 The outer end of the table is supported by a pedestal comprising legs 12 connected adjacent their lower ends by the cross piece 13, the legs being provided with wheels 14. The legs are supported by the braces 15, thus providing a rigid pedestal. At the outer end the table is provided with a hand-rail 16 for convenience in manipulation.

45 The front cross member 5 is provided with bumpers 17 which coact with the cross piece 13 when the table is fully telescoped into the frame.

50 On the under sides of the frame I mount

55 lamp housings consisting of the outer side wall 18, a bottom wall 19, the top wall 20 and end walls 21. The housings open inwardly and constitute side walls of the cabinet. A top 22 extends between the top walls of the 60 housings. The screens 23 are disposed between the top cross members 4 and the top 22 for ventilation purposes.

Electric lamps 25 are mounted on the top 65 walls of the housings with their electrodes 26 and 27 within the housings. As the details of these lamps form no part of my present invention they are not further described herein.

Between the lamps I mount rheostats designated generally by the numeral 24. The relation of the rheostats to the lamps is shown in Fig. 3. The lamps are controlled from 70 switches 28, there being a switch for the lamps of each housing.

The guard rails 29 project upwardly from 75 the inner edges of the bottoms 19 of the lamp housings providing troughs at the bottom of the housings to receive the material falling from the lamps, the guards also serving to protect the patients and the pad or 80 mattress conventionally shown at 30 in Fig. 1.

My improved therapeutic apparatus is especially designed for administering light treatments, although the lamp elements may, if desired, be of a character especially 85 adapted for the generating of heat. The apparatus is especially adapted for use in hospitals and the like where a portable apparatus is particularly desirable.

Having thus described my invention what 90 I claim as new and desire to secure by Letters Patent is:

1. In a therapeutic apparatus, the combination of a cabinet frame comprising uprights and top and bottom side and end rails connecting said uprights, track supporting brackets projecting inwardly from said uprights, tracks carried by said brackets, a table provided at its inner end with rollers traveling on said tracks and at its outer end with a wheeled pedestal whereby the table is slidably supported so that it may be withdrawn from and telescoped into the cabinet, lamp housings comprising outer side, top, bottom and end walls mounted on the sides of 95 said frame and constituting the side walls of the cabinet, guards projecting upwardly 100 from the inner edges of the lamp housing 105

bottoms providing troughs at the bottom, a top extending between the top walls of said lamp housings, and arc lamps mounted on the top walls of the housing with their electrodes within the housings.

2. In a therapeutic apparatus, the combination of a cabinet frame comprising uprights and top and bottom side and end rails connecting said uprights, track supporting brackets projecting inwardly from said uprights, tracks carried by said brackets, a table provided at its inner end with rollers traveling on said tracks and at its outer end with a wheeled pedestal whereby the table is slidably supported so that it may be withdrawn from and telescoped into the cabinet, lamp housings comprising outer side, top, bottom and end walls mounted on the sides of said frame and constituting the side walls of the cabinet, a top extending between the top walls of said lamp housings, and lamps within the housings.

3. In a therapeutic apparatus, the combination of a cabinet comprising a frame, tracks on said frame, a table provided at its inner end with rollers traveling on said tracks and at its outer end with a wheeled pedestal whereby the table is slidably supported so that it may be withdrawn from and telescoped into the frame, lamp housings comprising outer side, top, bottom and end walls mounted on the sides of said frame and constituting the side walls of the cabinet, guards projecting upwardly from the inner edges of the lamp housing bottoms providing troughs at the bottom, a top extending between the top walls of said lamp housings, and arc lamps disposed with their electrodes within the housings.

4. In a therapeutic apparatus, the combination of a cabinet comprising a frame, tracks on said frame, a table provided at its inner end with rollers traveling on said tracks and at its outer end with a wheeled pedestal whereby the table is slidably supported so that it may be withdrawn from and telescoped into the frame, lamp housings comprising outer side, top, bottom and end walls mounted on the sides of said frame and constituting the side walls of the cabinet, a top extending between the top walls of said lamp housings, and lamps within the housings.

5. In a therapeutic apparatus, the combination of a frame, lamp housings comprising outer side, top, bottom and end walls mounted on the sides of said frame and constituting the side walls of the cabinet, guards projecting upwardly from the inner edges of the lamp housing bottoms providing troughs at the bottom, a top extending between the top walls of said lamp housings, and arc lamps mounted on the top walls of the housing with their electrodes within the housing.

6. In a therapeutic apparatus, the combination of a frame, tracks on said frame, a table provided with rollers at its inner end traveling on said tracks and at its outer end with a wheeled pedestal so that the table can be withdrawn or telescoped into the same, lamp housings open at their inner sides disposed in the sides of the frame and constituting side walls of the cabinet, a top extending between said lamp housings, and arc lamps mounted on the outside of said lamp housings with their electrodes disposed within said housings.

7. In a therapeutic apparatus, the combination of a frame, tracks on said frame, a table provided with rollers at its inner end traveling on said tracks and at its outer end with a wheeled pedestal so that the table can be withdrawn or telescoped into the same, lamp housings open at their inner sides disposed in the sides of the frame and constituting side walls of the cabinet, and a top extending between said lamp housings.

8. In a therapeutic apparatus, the combination of a frame comprising uprights and top and bottom side and end rails connecting said uprights, track supporting brackets projecting inwardly from said uprights, tracks carried by said brackets, and a table provided at its inner end with rollers traveling on said tracks and at its outer end with a wheeled pedestal whereby the table is movably supported to be withdrawn from or telescoped into said frame.

9. In a therapeutic apparatus, the combination of a frame, tracks on said frame, a table provided with rollers at its inner end traveling on said tracks and at its outer end with a wheeled pedestal so that the table can be withdrawn or telescoped into the same, lamp housings open at their inner sides disposed in the sides of the frame and constituting side walls of the cabinet, and a top extending between said lamp housings.

10. In a therapeutic apparatus, the combination of a cabinet frame comprising uprights and top and bottom side and end rails connecting said uprights, lamp housings comprising outer side, top, bottom and end walls mounted on the outer sides of said frame and constituting the side walls of the cabinet, guards projecting upwardly from the inner edges of the lamp housing bottoms providing troughs at the bottom, a top extending between the top walls of said lamp housings, and arc lamps mounted on the top walls of the housing with their electrodes within the housings.

11. In a therapeutic apparatus, the combination of a cabinet frame comprising uprights and top and bottom side and end rails connecting said uprights, lamp housings comprising outer side, top, bottom and end walls mounted on the sides of said frame and con-

stituting the side walls of the cabinet, a top extending between the top walls of said lamp housings, and lamps within the housings.

12. In a therapeutic apparatus, the combination of a cabinet comprising a frame, lamp housings comprising outer side, top, bottom and end walls mounted on the sides of said frame and constituting the side walls of the cabinet, guards projecting upwardly from the

inner edges of the lamp housing bottoms providing troughs at the bottom, a top extending between the top walls of said lamp housings, and arc lamps disposed with their electrodes within the housings.

In witness whereof I have hereunto set my hand.

NORRIS E. GOODRICH.
